US0D1042331S

(12) **United States Design Patent** (10) **Patent No.:** **US D1,042,331 S**
(45) **Date of Patent:** **** Sep. 17, 2024**

(54) **DOCKING STATION**

(71) Applicant: **Amazon Technologies, Inc.**, Seattle, WA (US)

(72) Inventors: **Christopher Clive Jones**, San Francisco, CA (US); **Gregory Germe**, Orinda, CA (US)

(73) Assignee: **Amazon Technologies, Inc.**, Seattle, WA (US)

(**) Term: **15 Years**

(21) Appl. No.: **29/913,025**

(22) Filed: **Sep. 26, 2023**

Related U.S. Application Data

(62) Division of application No. 29/851,617, filed on Aug. 30, 2022, now Pat. No. Des. 1,008,270.

(57) **CLAIM**

The ornamental design for a docking station, as shown and described.

DESCRIPTION

FIG. 1 is a top, front, right-side perspective view of a docking station;

FIG. 2 is a bottom, back, left-side perspective view thereof;

FIG. 3 is a top, back, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the docking station that form no part of the claimed design.

1 Claim, 9 Drawing Sheets
